CLAIM

The ornamental design for a file organizer, as shown and described.

DESCRIPTION

FIG. 1 is a perspective view of a file organizer showing my new design;

FIG. 2 is a side elevation view thereof;

FIG. 3 is a partially opened side perspective view thereof;

FIG. 4 is another partially opened side perspective view thereof;

FIG. 5 is a third partially opened side perspective view thereof;

FIG. 6 is a fourth partially opened side perspective view thereof;

FIG. 7 is a completely opened side perspective view thereof;

FIG. 8 is another side perspective view thereof in a closed state;

FIG. 9 is a front elevation view thereof; and,

FIG. 10 is a top elevation view thereof.
